UNITED STATES PATENT OFFICE.

CHESTER H. CLARK, OF GALLUP, NEW MEXICO.

GAME.

Application filed September 29, 1926. Serial No. 138,486.

The object of this invention is to provide a game suitable for any number of players, each of whom shall have a set representing a particular country or nation, represented by a set of fourteen cards all carrying the flag of that nation, in the upper left hand corner, when the cards are held in either direction with numbers below the flag, and the name of the country below the number. 5 To the right of the flags are the words indicated in the drawings. A "peace" card has a white flag, the "peace base" card has a red cross in place of the flag, and another card termed a "home base" has a flag to 10 match the set.

The first thirteen cards of the set are numbered preferably in the upper left hand corners under the flags, the series of numbers from one to thirteen being provided for in 15 this manner, the "peace" card, "peace base" card and "home base" card having no numbers.

In playing the game, the "peace" card is shuffled with the thirteen cards, while the 20 colored counters are placed upon the "home base" card in front of each player. The counters have different values assigned thereto, indicating the assumed wealth of the country represented by the player having 25 the counters. Hence, each country enters the "War versus Peace" game with equal resources and an equal armament.

Players are eliminated during the game, as indicated below, one of the countries, represented by the player finally remaining in 30 the game, winning "universal empire", or should the "peace base" have the greater number of counters, a "universal peace" is declared.

40 In the drawings forming part of this application,

Figure 1 shows twelve of the cards.

Figure 2 illustrates a "major" card carrying special wording, indicating the branches 45 of the service, this card, or a similar card, being used in each set with the name of the proper country thereon.

Figure 3 shows a "home base" card of one 50 of the sets, all sets being similarly supplied.

Figures 4, 5 and 6 show sample cards belonging to the sets of other countries and other players.

Figure 7 illustrates a "peace base" card.

Figure 8 shows a "peace" card, one of 55 which is used with each group of players.

Figures 9 and 10 show respectively a counter in plan, and in edge elevation.

Referring to Figure 1, the first twelve cards are not only designated by the reference characters 1 to 12, inclusive, but the 60 cards are actually numbered from 1 to 12 in practice. In Figure 2, card 13 is similarly numbered, this being termed a "major" card.

The cards of Figures 3, 7 and 8 are designated 65 14, 15, 16.

In Figures 4, 5 and 6, cards 17, 18 and 19 represent cards of other sets, that is sets belonging to other players and representing 70 other countries.

Counters 20 are shown in Figures 9 and 10, these counters are valued as indicated below and are to be the size of a silver quarter.

Rules.

75

Each player chooses a set of the cards representing a nation different from that of any other player, for which he hopes to win a "world empire", and thirty counters. The 80 player now puts the "home base" card in the center of the table in front of his position, and places the counters upon it. The "peace base" card is placed in the center of the "home base" cards.

The counters are divided as follows: 10 white valued at 100 million each; 10 red valued at 200 million each; 10 blue valued at 300 million. The total assumed national wealth of each nation being 6 billion in 90 gold reserve, plus the national resources of each nation, as shown on the cards, it will be seen that the nations enter the world's struggle with an equal gold reserve and armament.

Players.—Two or more players may play at the same game or there may be groups of four playing progressively.

Dealers.—The dealer is determined by all the cards up to and including number 13 of each set used and one "peace" card being put into a common pack and the player drawing the highest deals the first time around.

Dealing.—The dealer now gives one card at a time to each player and one to the center continuing in this manner until all the cards are dealt. The hand in the center is called the "reserve force", or shock troops.

Play.—The dealer now picks up his cards,

followed by the others (should any other player pick up his cards first he must contribute one white counter over to the "peace base"). Should he hold a "major" card, 5 he declares "Open for bids", whereupon the first player to his left not holding a "major" card opens the bids, and every one holding "major" cards, says "pass". The bids are continued in this manner until there are no 10 further bids, whereupon the successful bidder pays his bid into the "peace base", picks up his "reserve force", after he has discarded his hand. As soon as he has had time to arrange his cards, the first player to 15 the left of the dealer holding a "major" card or "13", says: "I declare war", whereupon all the other players pay him one red counter. The player places the lowest card in the suit he chooses and so on until all 20 the cards are played, one upon the other in piles directly in front of the player having the next card in higher rotation. If the dealer holds no "major" card he may say "Not for sale", discard his hand and pick 25 up the "reserve force", whereupon the first player to his left holding a "major" card, "declares war", and the play proceeds as before.

Change of suit.—When there is a pause 30 in the placing of cards, the player putting down the last card says: "Is the play blocked?", pause a moment and says: "I change suit". Whereupon all the other players surrender to him one white counter 35 and he announces the lowest card of the next suit.

Peace card.—The player holding the "peace" card has the right to play it when he gets the "change of suit", whereupon all 40 the other players pay him one red disk and a blue disk to the "peace base".

Player closing out hand first.—Calls for a white counter from the other players for each card they hold and a red counter to be 45 paid into "peace base" for each "major" card they hold. Should any one hold the "peace" card, they are forced to "sue for peace" and drop out of the game.

Play of major cards.—The player whose 50 turn it is to play the "major" card, or "13", says: "General engagement", and the other players surrender to him one blue counter each as the toll of the engagement. As a result of this stage of the "world war", there 55 are likely to be numerous engagements all over the several battle fronts and the game at this stage is very exciting.

A hand.—As soon as one player has disposed of all his cards, that is called a hand. 60 And as soon as he has received all of his plunder of war, the player to the left of the

first dealer deals again. When progressive tables are used, four hands are usually played when the two having the highest count progress, but if peace is higher than any, the difference is counted as a minus count on the score of such players. 65

Sue for peace or borrow.—When any nation has lost all its counters, the player may sue for peace or negotiate a loan equal to 70 his former gold reserve or six billion. Should he sue for peace he borrows only enough to finish out his present hand. After peace has been sued for, no other player can borrow more than enough to finish out his 75 hand.

Double and redouble.—As soon as one player has dropped out, all counts are doubled in number, and as soon as the second player drops out they are redoubled, that is, 80 for every former counter called for, four are called for with a redouble. In this way there is little time lost where players are thrown out of the play.

Winner.—The last player in the game 85 counts over the counters to see whether he or peace has won. If he has won there is a "universal empire" under his nation. Should peace win there is a "universal peace".

Armistice.—When cards are still held and 90 no change of suit can be made by any player, an armistice is forced and peace is declared.

Treaty control.—Should any player hold four "congresses", or four "peace envoys" or four "arbitration" cards, as soon as he may 95 acquire the right for a change of suit he may sue for peace and demand four blue counters from each of the other players, and four red counters to "peace base" for each "major" card held by any player. The 100 "peace" card counts as before by forcing the holder thereof to sue for "peace" and drop out of the game at the close of his hand.

Having described the invention what is claimed is:—

In a card game, a plurality of sets of cards, each set representing a different country and each set including cards carrying data representing military and civil resources, counters for use by each player, a major card entitling the holder thereof to special privilege, a card in each set for use in a central group, to which counters are contributed and from which loans may be made, and a peace card to be played into the central group and entitling the holder who makes the play to payments of counters from all of the other players, the two cards last named carrying characteristic designations. 110

In testimony whereof I affix my signature.
